UNITED STATES PATENT OFFICE

170,563

EDUCATIONAL DEVICE

Sylvia Zipkin, Philadelphia, Pa.

Application November 5, 1952, Serial No. 22,223

Term of patent 7 years

(Cl. D25—1)

To all whom it may concern:

Be it known that I, Sylvia Zipkin, a citizen of the United States, residing at Philadelphia, in the county of Philadelphia and State of Pennsylvania, have invented a certain new, original, and ornamental Design for an Educational Device, of which the following is a specification, reference being had to the accompanying drawing, forming part thereof.

The single figure is a front perspective view of an educational device, showing my new design.

I claim:

The ornamental design for an educational device, substantially as shown.

SYLVIA ZIPKIN.
